UNITED STATES PATENT OFFICE.

LUDWIG RELLSTAB, OF ZEIST, NETHERLANDS, ASSIGNOR TO SIEMENS & HALSKE, AKTIENGESELLSCHAFT, OF SIEMENSSTADT, NEAR BERLIN, GERMANY, A GERMAN CORPORATION.

ELECTRIC STEERING COMPASS.

Application filed November 20, 1920. Serial No. 425,584.

To all whom it may concern:

Be it known that I, LUDWIG RELLSTAB, a citizen of the German Empire, residing at Zeist, Netherlands, have invented certain new and useful Improvements in Electric Steering Compasses (for which I have filed applications in Germany, July 11, 1918, Patent No. 342,297; Denmark, July 8, 1919; Holland, July 11, 1919; Norway, July 28, 1919; and in England, October 23, 1919, Patent No. 134,226), of which the following is a specification.

My invention refers to electric compasses, and its particular object is to provide a device for indicating the deviations of a ship from the course in water ways having cables fed with electric currents disposed therein.

My invention substantially consists in an arrangement, whereby the induction currents resulting from the conductors submerged in the water are amplified by aid of auxiliary devices inserted in the circuit of the receiver loops on both sides of the ship, whereupon they are rectified and translated by means of direct current indicators. These latter may be constructed in any suitable manner, for instance, as shown in the drawings, in the form of simple needle galvanometers or as a moving coil system common to the loops on both sides of the ship, such instrument, as is well known, indicating the quotient of the currents.

The auxiliary devices for amplifying the induction current may consist in amplifier tubes of a well-known kind, such as Lieben relays, while for rectification for instance the same kind of relays or crystal detectors may be used. Owing to their merely indirect connection with the indicating instruments these devices can easily be arranged outside the wheel house so that in this room merely the indicating instruments are disposed, such instruments being preferably located within the same wall box with their pointers crossing each other.

In the drawings affixed to this specification and forming part thereof the preferred form of a steering system according to the present invention is illustrated in a purely diagrammatic manner.

In these drawings:

Fig. 1 shows an entire steering coil sys-

tem in which two galvanometers, one for each side of the ship, are cooperatively used as indicating means by crossing their indicators;

Figs. 2 and 3 show different connections of the four receiving loops with the indicating device, each figure showing the ship inclined and in parallel to the pilot cable or cables; and

Fig. 4 shows a moving coil system used in place of a pair of galvanometers for producing an indication.

Referring to Fig. 1, A and B are loops disposed on the port and starboard sides, respectively, of a ship, said loops being influenced by the induction currents resulting from a single cable lying in the middle (Fig. 3) or from two cables lying on the sides of the water way, as shown in Fig. 2. U₁ and U₂ are transformers inserted in the circuits of loops A and B, respectively, said transformers leading to amplifier tubes V₁ and V₂ respectively. The induction currents amplified thereby are then rectified by crystal detectors D₁ and D₂ respectively and conducted to needle galvanometers G₁ and G₂ respectively. The two galvanometers are combined so as to form a single instrument for instance of the size of an ordinary voltmeter with their pointers crossed, as shown for G₁, G₂ in Fig. 1 in full lines for zero position when no current is received by the loops. At equal deflection of both pointers in opposite directions the crossing point of the pointers ascends vertically on the center line m of the device, whereas at a greater deflection of one or the other galvanometer the crossing point will deviate laterally, as shown by dotted lines, the more so, the greater the difference between the deflections of the two instruments.

In the position shown in the drawing in dotted lines the pointer of the galvanometer G₂ has a greater deflection and in consequence thereof the crossing point K lies on the right hand side of the center line m of the box containing both galvanometers, it being indicated thereby that the ship has deviated to starboard from the middle of the water way and has approached the starboard cable lying in the water way (Fig. 2). If one such indicating device is provided

for the bow and for the stern, the two devices may be disposed together within a common box and arranged to have their center lines m in common, which line may be made permanently visible as a pilot line representing the cable, so that the parallel or angular position of the line, connecting the two crossing points K of their indicators, relatively to the pilot line m allows to ascertain the equal or different deviation of the bow or stern from the course. This form is shown in Fig. 2, which illustrates the vessel inclined to the imaginary center line between the two cables C , C , and which also shows the vessel in parallel to, but laterally of this line. The imaginary center line is indicated on the apparatus mounted on the vessel by the dash-dot line m , m . The line K , K in each case indicates the direction in which the vessel is angularly inclined to the center line between the two cables. The galvanometer coils G_1 — G_4 indicated in Fig. 1, are shown in Fig. 2 only in a general way in connection with their respective receiving coils A_1 , B_1 , the actual circuits being the same as shown in Fig. 1 with regard to coils G_1 , G_2 .

Fig. 3 shows a vessel in two positions guided by one single cable C . In this case, however, the dash-dot line m , m drawn through the longitudinal center of the coil system represents the center line of the ship, whereas the line K , K represents the position of the cable, so that out of the angular relation between the two lines the angular position of the vessel relatively to the cable may be ascertained. In this case, however, the stern receiving coils A_1 , B_1 are connected with the bow indicating coils G_1 , G_2 , the bow receiving coils A , B with the stern indicating coils G_3 , G_4 . This cross connection in this case is necessary to obtain correct indication. However, no matter what the line m , m represents, whether the center line of the vessel or the cable, it always represents a pilot line by means of which the angular position of this vessel relatively to the pilot cable may be directly read off. Therefore, when I refer in the annexed claims to a "pilot line," this line may represent any of the lines m , m shown in the drawings, so long as this line runs through the longitudinal center of the indicating instrument, so that the indications of the latter occur symmetrically to the right or left of this line.

The amplifier tubes V_1 , V_2 are permanently fed with direct current as long as the operation of the device is required, so that on one of them getting damaged the closed circuit current which also influences the galvanometers is interrupted and the pointer of the instrument in question is no more deflected. This is so conspicuous that it is bound to be observed immediately.

Instead of needle galvanometer pairs G_1 , G_2 and G_3 , G_4 , one may employ as well, moving coil systems well known in the art, as illustrated for instance in Fig. 4. Such a system is provided with a stationary coil 70 a , b respectively for each loop A and B , the coils a , b being mounted so that their center planes of winding symmetrically cross each other. In alignment with the intersection line of these two planes and 75 freely rotatable on this line as an axis, a third coil c is disposed, which tends to adjust itself angularly relatively to the fixed coils in accordance with the resultant electromotive forces generated by the currents 80 flowing in the two fixed coils a , b , thereby indicating the quotient of the currents of the two fixed coils. An indicator d is fixed to coil c , which cooperates with a scale e and thus gives the same indications which are 85 obtained by the crossing points K of the two cooperating galvanometer pairs in Figs. 1 to 3.

I claim:

1. In radio pilot cable systems for vessels, 90 having a pilot cable disposed on the fair-way bottom and supplied with alternating current, in combination at least one pair of receiver loops, one loop disposed on each side of the vessel to be piloted, the circuit 95 of each loop including means for amplifying and rectifying the alternating currents induced in said loop by said cable current and an indicating instrument having a pilot line extending through the longitudinal 100 center of said indicating instrument and means connected with said loop circuits for directly visibly indicating by the joint action of said loop currents the position of the vessel relatively to the cable. 105

2. In radio pilot cable systems for vessels, having a pilot cable disposed on the fair-way bottom and supplied with alternating current, in combination at least one pair of receiver loops, one loop disposed on each 110 side of the vessel to be piloted, the circuit of each loop including means for amplifying and rectifying the alternating currents induced in said loop by said cable current and an instrument of the galvanometer type, 115 having a pilot line extending through the longitudinal center of said indicating instrument, said instrument being connected with both of said loop circuits for directly visibly indicating by the joint action of said 120 loop currents the position of the vessel relatively to the cable.

3. In radio pilot cable systems for vessels, 125 having a pilot cable disposed on the fair-way bottom and supplied with alternating current, in combination at least one pair of receiver loops, one loop disposed on each side of the vessel to be piloted, the circuit of each loop including means for amplifying and rectifying the alternating currents 130

- induced in said loop by said cable current and an instrument of the galvanometer type, having two coils disposed side by side and each connected with one of said loops each 5 coil having a pointer crossing the pointer of the other coil, said instrument also having a pilot line extending through the longitudinal center of said indicating instrument, the crossing point of said pointers varying laterally of said line in accordance with the difference between the currents induced in the individual loops, caused by the deviation of the vessel from its course set by said cable.
- 10 4. In radio pilot cable systems for vessels having a pilot cable disposed on the fairway bottom and supplied with alternating current, in combination two pairs of receiver loops, one pair disposed near the bow, 15 the other pair near the stern of the vessel, one loop of each pair being disposed on each side of the vessel, the circuit of each loop of each pair including means for amplifying and rectifying the alternating current induced in said loop by said cable current, 20 and an indicating device having a pilot line extending through the longitudinal center of said indicating instrument and means connected with the loop circuits of each pair, 25 and adapted to directly visibly indicate by the joint action of its loop currents the position of the vessel portion, at which said loop pair is located, relatively to said pilot line, the position points given by said two 30 pairs relatively to said line indicating the 35 angular relation of the entire vessel to said pilot cable.
5. In radio pilot cable systems for vessels having a pilot cable disposed on the fairway bottom and supplied with alternating current in combination two pair of receiver loops, one pair disposed near the bow, the other pair near the stern of the vessel, one loop of each pair being disposed on each side of the vessel, the circuit of each loop 40 of each pair including means for amplifying and rectifying the alternating current induced in said loop by said cable current, and an indicating device comprising an instrument of the galvanometer type for each 45 loop pair, having two coils disposed side by side, and each connected with one of said loops, each coil having a pointer, crossing the pointer of the other coil, a pilot line on 50 said indicating device running between said two instruments and located midway between the two coils of each instrument, the crossing point of the pointers of each instrument varying laterally of said line in accordance with the difference between the 55 currents induced in its individual loops, caused by the deviation of the vessel portion at which said loop pair is located from its course set by the cable, the position points given by the pointer of said two pairs relatively to said line indicating the angular 60 relation of the entire vessel to said pilot cable.
- 65 In testimony whereof I affix my signature.

LUDWIG RELLSTAB.
